SMOKING STAND

Elton L. Andrews and James A. Waller,
Bradenton, Fla.

Application August 4, 1950, Serial No. 11,592

Term of patent 7 years

(Cl. D85—2)

To all whom it may concern:

Be it known that we, James A. Waller and Elton L. Andrews, citizens of the United States of America, residing at Bradenton, in the county of Manatee and State of Florida, have invented a new, original, and ornamental Design for Smoking Stand, of which the following is a specification, reference being had to the accompanying drawing, forming a part thereof, wherein the single figure of the drawing is a perspective view of a smoking stand, showing our new design.

We claim:

The ornamental design for a smoking stand, as shown.

ELTON L. ANDREWS.
JAMES A. WALLER.
